UNITED STATES PATENT OFFICE.

EDWIN V. MUNDY, OF DULUTH, MINNESOTA, ASSIGNOR OF ONE-FOURTH TO
HARRY C. CRAWFORD, OF SAME PLACE.

DESIGN FOR A BOOT AND SHOE CALK.

SPECIFICATION forming part of Design No. 15,491, dated October 28, 1884.

Application filed July 19, 1884. Term of patent 14 years.

To all whom it may concern:

Be it known that I, EDWIN V. MUNDY, of Duluth, in the county of St. Louis and State of Minnesota, have invented and produced a new and original Design for a Boot and Shoe Calk, of which the following is a specification.

My design for a boot and shoe stud or calk consists in a pointed head of conical configuration mounted on the frustum of a cone having a reverse taper to the pointed portion of the head, and surmounted in its turn by a cylindrical extension tapering to a point at its top, and ornamented throughout its length by interrupted or broken oblique grooves or indentations, giving a barb-like appearance to said extension or shank, as herein shown and described.

Reference is to be had to the accompanying drawing, forming part of this specification, which represents a longitudinal view, upon an enlarged scale, of a boot or shoe calk embodying my design.

The lower portion, *a*, of the head of the calk terminates in a point below, and is of conical configuration, and its upper portion, *b*, is in the shape of the frustum of a cone tapering in a reverse direction to the lower portion, *a*, from the outer margin of the head of said portion.

c indicates the shank of the calk, which is in the form of a round column or cylindrical projection mounted on the frustum of the cone *b*, and here shown as terminating in a point,

d, at top. This cylindrical portion or extension *c* may either present a plain appearance on its surface, or it may be indented with interrupted reverse oblique grooves *e*, giving to it an ornamental broken, roughened, or barb-like appearance throughout its length. 35

I claim—

1. The within-described design for a boot and shoe calk, which consists in a head, the lower portion, *a*, of which terminates in a point, and is of conical configuration, having plain faces or sides and straight edges, and its upper portion, *b*, in the form of the frustum 45 of a cone tapering in a reverse direction to the lower portion, *a*, and having mounted on it a cylindrical extension, *c*, terminating above in a point, *d*, as shown.

2. The within-described design for a boot 50 and shoe calk, which consists in a shank, *c*, of cylindrical form, terminating above in a point, *d*, with interrupted grooves or oblique indentations *e* in its surface, giving it a barbed-like appearance, and mounted upon a head, *a* *b*, 55 the upper portion of which is in the form of the frustum of a cone, and its lower portion of conical shape terminating in a point, as shown.

EDWIN V. MUNDY.
